**GASEOUS GLOW TUBE CONTROLLED
MUSICAL INSTRUMENT**

Donald M. Park, Raleigh, N.C., assignor to Park-Baker
Electronic Development Corporation, Raleigh, N.C., a
corporation of North Carolina

Filed Jan. 15, 1962, Ser. No. 166,159
11 Claims. (Cl. 84—1.03)

My invention is concerned with a rhythm control for a musical instrument which generates percussion sounds electronically. More specifically, the invention is concerned with a gaseous glow tube switching device for such an instrument.

One of the more popular electronic musical instruments is known as a "side-man" and its purpose is to produce percussion rhythms. The side-man is usually comprised of ten or more "instruments" such as bass drum, tom toms, blocks, cymbals and the like which may be electronically combined to produce rhythms such as the tango, rhumba, fox trot or waltz. The "instruments" are produced electronically by phase shift oscillators or other noise generators and when played manually or automatically as accompaniment with an electronic organ they produce pleasing repetitive musical effects. Since the side-man furnishes a concrete example of where my invention may be applied, it is in connection with a side-man type circuit that my invention is explained.

In prior art side-man devices the switching speed, that is the rhythm speed or tempo, from one instrument to another is controlled by a conventional mechanical variable speed drive. This has introduced various well-known noise and mechanical problems. A conventional wiper switch and wiring has been employed with the drive which has required the use of substantially large numbers of brushes, connection wires and contacts. Due to the number of contacts and various mechanical components required to produce conventional rhythms, the prior art side-man systems have further required a relatively large motor drive and generally have not been found adaptable to complex rhythms. Since speed control has required a manual mechanical movement the tempo of any particular rhythm has had to remain substantially constant.

A general object of this invention is therefore to provide a considerably improved rhythm control and instrument selection device for side-man type electronic musical circuits.

Another object is to provide a means to electrically pulse instrument generators which gives maximum latitude to complex rhythms.

Another object is to provide a means to electrically pulse instrument generators such that the rhythm tempo may be electrically controlled by the person playing.

Another object is to provide an instrument selection device which uses gaseous tubes as an integral part of the pulsing circuit so as to substantially reduce the wiring and switching complexity.

Another object is to provide a general electrical pulse selection system which uses gaseous tubes as an integral part of the pulsing circuit so as to substantially reduce the wiring and switching complexity.

These and other objects of the invention will become apparent as the description proceeds and in the drawings, in which:

FIGURE 1 is a schematic diagram illustrating the principal components of a side-man system.

FIGURE 2 is a schematic diagram illustrating an embodiment of a side-man system according to the invention.

FIGURE 3 is a portion of the diagram of FIGURE 2.
FIGURE 4 is a portion of FIGURE 2 with various

2

substitutions illustrating another embodiment of the invention.

Generally speaking, the purpose of a side-man device is to provide a source of repetitive percussion rhythms. The conventional side-man circuit is equipped with means to selectively establish limited number of both rhythms and tempos. FIGURE 1 illustrates the general system employed. The drive 10 of the conventional system is a constant speed motor and the speed control 11 consists in practice of a roller which can be moved back and forth along the radius of a disc driven by the constant speed motor. The roller in turn acts to drive a wiper switch indicated at 12 which through a series of wiper brushes and a considerable number of concentrically arranged contacts serves to selectively transmit pulses from a voltage source indicated at 13 through conventional wiring to any one or combinations of various phase shift oscillators that act as the designated tone generators 14 and whose output is fed to an amplifier 15 and speaker 16.

In order to be able to change from one rhythm to another in the conventional system the pulses are fed through a multi-wafer selector switch 14 that has a movable contact on each wafer subject to a common manual control. By moving the selector switch 17, predetermined circuits can be established between the wiper switch 12 contacts and selected tone generators 14. In order to accomplish all of the desired rhythms usually desired, the conventional wiring system necessarily employs several concentric rows of contacts in the wiper switch 12 and a rather complex multi-bank selector switch 17. This is particularly true since the conventional system does not provide any means to tie the wiper switch contacts into more than one rhythm circuit. The present invention on the other hand provides a circuit means which allows the wiper switch contacts to appear in a plurality of rhythm circuits while maintaining the contacts in electrical isolation. The present invention is especially concerned with simplified means for establishing the speed or tempo, and for establishing circuits between the pulse generator section, that is the wiper switch, and the music section, the tone generators.

Dealing first with the matter of tempo and the diagram of FIGURE 2, the present invention employs a synchronous motor 20 driven by a variable frequency oscillator 21 which is under an appropriate frequency control 22 thereby governing the motor speed and consequently the tempo. The motor 20 may be of the familiar clock timing motor type since the invention allows a substantial reduction in wiper switch contacts which in turn substantially reduces the wiper switch load that must be driven. A suitable type oscillator is a resistance-capacitance type oscillator with either resistance or capacitance control and in a power class sufficient to meet the nominal power required to operate a timing motor. With such an arrangement speed or tempo may be controlled electrically by regulating the position of a resistor or capacitance. Through any of several well-known arrangements, the resistor or capacitor positioning may be adapted for remote operation thereby enabling remote operation of the tempo.

Motor 20 is connected to a wiper switch generally designated at 23 and drives a constantly rotating wiper arm indicated at 24. Wiper arm 24 is electrically connected to a voltage source labelled as "3V_s" in the drawing and whose meaning is explained later on. As the wiper arm rotates it periodically connects this source of voltage in consecutive time sequence through a wiper brush 25 to the eight contacts shown. The number of wiper contacts will, of course, vary. The wiper switch may for example have a much larger number of contacts distributed over several concentric rows and contacted by several brushes. For purposes of simplification, only a limited

number of contacts are shown. It should be pointed out here however that one of the advantages of the invention is that the number of wiper switch contacts required is greatly reduced as compared to the conventional system and as will be seen later, even this simple array of eight wiper switch contacts provides a relatively wide selection of rhythms.

Depending on the speed of rotation of wiper arm 24 as controlled by the frequency control 22, the eight contacts thus receive periodic voltage pulses at time intervals determined by this speed. These pulses are used to trigger selected ones of the tone generators. For purposes of simplification, the invention is explained with the use of three tone generators, namely, a drum indicated at 26, blocks indicated at 27 and cymbals indicated at 28. The number of tone generators may vary and it is not uncommon to find as many as ten separate tone generators in side-man circuits. The outputs of the tone generators are combined and fed to an amplifier as indicated at 29 and to a speaker as indicated at 30.

Connected to the tone generators is a selector switch generally designated at 31 and whose purpose is to furnish a manual switching means whereby after the circuits between the wiper switch 23 and selector switch 31 are fixed, the selector switch 31 can be manually moved to various positions so as to change the particular tone generators to which the voltage pulses are directed. Selector switch 31 is illustrated as comprising three wafers or banks 32, 33 and 34 each of which by way of example has five contacts and a slider connected to respective ones of the tone generators. For example, it will be seen that the slider for bank 32 is connected to the drum 26, the slider for bank 33 is connected to the blocks 27 and the slider for bank 34 is connected to the cymbals 28. It will be understood that the sliders are physically connected so that they change position together and are controllable by a single manual control knob, not indicated. In this way, the operator can switch to different positions so as to select only a particular tone generator or a particular combination of tone generators.

The output of each slider is fed through suitable tone generator input resistors 35, 36, 37 to ground. Pulsing of particular tone generators will thus depend on the position of the selector switch sliders and the speed or tempo at which they are pulsed will depend on the speed of the motor 20 which in turn will depend on the setting of the controlling electrical element of frequency control 22. We will now look to what is one of the most important aspects of the invention, namely, the manner in which circuits are made between the pulse generator, the wiper switch, contacts and the contacts feeding the tone generators and which allows a plurality of connections to be made to each wiper switch contact.

An important aspect of the circuits between the wiper switch and selector switch is the employment of gaseous glow tubes and before proceeding to the actual circuitry, an explanation is made of those characteristics of these tubes that are of particular interest to the invention. Examples of these tubes are found in the very inexpensive neon Ne-2 and Ne-96 types. Here, it is important to recognize that until such a tube breaks down or fires there is near perfect electrical isolation between the tube electrodes. Another characteristic of interest is that the voltage across the tube immediately prior to firing is substantially higher than is the voltage across the tube after the tube has fired.

In explanation of the invention, the label "V_s" is used to mean the voltage across the tube necessary to sustain firing after the tube has fired. Thus, "3V_s" means three times this voltage and "2V_s" means twice this voltage. In the one embodiment illustrated it will be seen that he 3V_s source is used to pulse a particular tone generator through a particular circuit containing gaseous tubes adapted to fire when under the influence of this source whereas the 2V_s sources are used as bias voltages to

prevent other circuits and tone generators from being activated by preventing firing of the tubes even though they are tied into the circuits that are activated. In a further embodiment hereafter described a 2V_s source and V_s biasing voltages are used for similar purposes.

To illustrate how the gaseous tubes are employed to reduce contacts and circuits and to enhance the programming possibilities, three of the wiper switch contacts are illustrated as they might be wired into an actual side-man circuit. In the selector switch, two typical positions are shown, one in solid lines and one in dotted lines and as previously mentioned the tone generators are limited to three in number so as to simplify the explanation. While a relatively simple circuit arrangement of this kind brings out the invention, it should be appreciated that the invention's greatest advantages are exhibited in a more complex circuit since more wiper switch contacts, more circuits and more rhythms would be involved giving more opportunity for the invention to be applied through circuit simplification.

Referring to FIGURE 2, when the selector switch sliders are in the left hand position, indicated in solid lines, the respective instruments will be connected through their respective sliders to the left hand selector switch contacts such as the contacts furthest to the left in wafer banks 32, 33, 34. Assuming the selector switch sliders are in such position, circuits are established and can be traced between the wiper switch contacts and the instruments. Limiting ourselves to contacts 1 and 2 of the wiper switch 30 and the left hand contact of wafer bank 32, we can trace circuits such as illustrated by FIGURE 3, representing a portion of FIGURE 2.

In FIGURE 3, it can be seen for example that a circuit between the 3V_s pulse source and drum 35 is completed when the brush 25 contacts contact 1 of the wiper switch. This circuit will include gaseous tubes 38 and 39 in series, which are adapted to be fired by the 3V_s source so as to cause a controlling voltage to appear across the input resistor 35. Now when brush 25 reaches contact 2, it will be seen that a separate circuit to the drum 26 is established which includes the previously mentioned gaseous tube 39 and in addition a separate gaseous tube 40 which is selected so as to have a similar firing characteristic. From this, it can be seen that contacts 1 and 2 are tied together and that the gaseous tube 39 is common both to the contact 1 circuit and the contact 2 circuit being discussed. However, by biasing the contact 1 circuit and the contact 2 circuit with the 2V_s voltage illustrated, any tendency for the 3V_s pulse to fire tubes 38 and 40 simultaneously is avoided. In this particular instance it is convenient to use a common 2V_s to bias both circuits. With such a basic arrangement, it can be seen that each of the wiper switch contacts can actually be tied into several principal circuits and that at least some 55 of the gaseous tubes may appear in a plurality of circuits.

Reverting back to FIGURE 2, it will be seen that blocks 27 are tied into contacts 1 and 3 of the wiper switch 23. As to contact 1, the circuit connecting the blocks with the wiper switch includes gaseous tubes 41 and 42. It is to be further seen that contact 3 of wiper switch 23 is tied into the drum 26 through gaseous tubes 44 and 39 and is tied into the cymbals 28 through the gaseous tubes 45 and 46 and the left hand contact of wafer 34 of selector switch 31.

With the arrangement described in FIGURE 2, as the wiper arm 24 brings brush 25 in contact with contact 1 of wiper switch 23, the 3V_s voltage will pulse circuits to the drum 26 and blocks 27 but not the cymbals 28 even through the cymbals are tied into this contact 1. Then as the wiper arm 24 continues to rotate in the arrow direction indicated, brush 25 will contact the contact 2 which will act to pulse the drum 26 but not the blocks 27 or cymbals 28 even though both are tied back into lines which connect with this contact 2. Upon 70 reaching contact 3, all three instruments will be pulsed 75

and accordingly the sound coming out of speaker 30 will represent a blending of all three tones.

While not shown, it is obvious that each of the eight wiper switch contacts can be tied into various circuits and can be used to establish circuits in the manner of the circuits explained in connection with the first three contacts. In each instance the electrical contacts in the pulse generator, the wiper switch, are electrically isolated one from the other because there is never enough potential difference to fire the gaseous tubes along the secondary path connecting the contacts. Thus, the gaseous tube circuits described serve to direct the pulses along the correct principal paths, to the correct instruments and at the correct times.

Referring next to the dotted line positions of the wipers in selector switch 31, it will be assumed that the selector switch has been rotated so as to bring each wiper to the second contact from the left. Here, the circuits are revised substantially from the circuits previously discussed. For example, with the selector switch wipers in the positions indicated in dotted lines, both contact 1 and contact 2 of the wiper switch when connected to the $3V_s$ source will act to pulse the drum 26 but no other instrument. Contact 3 when connected to the $3V_s$ source will pulse the drum 26 and cymbals 28 under this arrangement. To have this change in musical arrangement, it will be noticed that only the short leader connections 47, 48 are required. It should further be noticed that the wiper switch contacts remain effectively isolated even though tied together and into a plurality of circuits.

A somewhat indirect advantage which has been observed as arising out of use of gaseous tubes in the manner described is that the invention circuits tend to pulse amplify the applied pulses. Such amplification is accomplished by reason of the difference between breakdown and sustaining voltages of the gaseous tube. This difference appears at the output, the tone generator input, of the network as an increased voltage due to the low impedance input of the pulse source. Accordingly, a sharp and prominent pulse will appear at each respective tone generator each time a circuit is established between the pulse generator source and the respective tone generator.

In FIGURE 4, there is shown a portion of FIGURE 2 with a different glow tube arrangement which illustrates a further embodiment of the invention. For purposes of simplification only portions of the pulse generator and selector switch sections are shown. In the embodiment of FIGURE 4, it will be seen that instead of having two tubes in series in each of the principal paths, only one tube is employed. Accordingly, a lesser pulse voltage indicated as $2V_s$ may be used to open the paths for pulse transmission and a lesser biasing voltage indicated as V_s may be used to block the paths connecting the wiper switch contacts. The reader will understand that the general operation of the one tube per path system is similar to the previously discussed two tubes per path system with the exception of the voltages employed and therefore no further detailed discussion is believed necessary.

While a specific form of the invention has been described, it will be understood that variations thereof may be employed without departing from the scope of the invention. For example, other drive and speed control arrangements could be used in combination with the pulse generator section. A multi-vibrator oscillator and various other electrical indexing rotating devices could for example furnish the power and timing requirements of a system employing the glow tube circuits of this invention.

What I claim is:

1. In an electronic music circuit having a plurality of tone generators to be selectively pulsed at given times; a pulse generator including a first set of contacts, a voltage pulse source and means selectively connecting said source to said first contacts in predetermined time sequence; switching means including a second set of contacts con-

nected to respective ones of said tone generators; a network of circuits establishing principal electrical paths from particular first contacts to particular second contacts and to the respective tone generators connected thereto, portions of said principal paths being in common thereby establishing secondary paths between various pairs of said first contacts; glow discharge tubes placed in each of said paths and adapted to establish said principal paths as pulse transmitting paths responsive to said source and said secondary paths as non pulse transmitting thereby enabling said first contacts to be electrically isolated one from the other while connected to a plurality of said principal paths.

2. In an electronic music circuit as claimed in claim 1 including an additional voltage source continuously biasing said second paths against response to said pulse source.

3. In an electronic music circuit as claimed in claim 1 wherein each of said principal paths includes at least two of said tubes in series.

4. In an electronic music circuit as claimed in claim 1 wherein said switching means includes manual control means allowing each of said tone generators a choice of particular ones of said second contacts to which it is connected thereby enabling said tone generators to be selectively connected to particular ones of said first contacts.

5. In an electronic music circuit as claimed in claim 1 wherein said means for connecting said source to said first contacts comprises a rotating type switch, a synchronous motor drive, a variable frequency drive source and a frequency control for said drive source thereby enabling the tempo of said music to be determined by the setting of said control.

6. In an electronic music circuit having a plurality of tone generators to be selectively pulsed at given times; a rotating type pulse generator including a first set of contacts, a voltage pulse source, a synchronous motor drive, a variable frequency voltage source for said drive and a frequency control enabling the tempo of said music to be controlled thereby; switching means including a second

set of contacts selectively connectable to particular ones of said tone generators; a network of circuits establishing principal electrical paths from particular first contacts to particular second contacts, portions of said principal paths being in common thereby establishing secondary paths between various pairs of said first contacts; a plurality of glow discharge tubes placed in each of said paths and adapted to establish said principal paths as pulse transmitting paths responsive to said source and said secondary paths as non pulse transmitting thereby enabling said first contacts to be electrically isolated one from the other while connected to a plurality of said principal paths and voltage biasing means biasing said secondary paths against response to said pulse source.

7. In an electronic circuit having a plurality of electrical devices to be selectively pulsed at given times; a pulse generator including a first set of contacts, a voltage pulse source and means selectively connecting said source to said first contacts in predetermined time sequence; switching means including a second set of contacts connected to respective ones of said devices; a network of circuits establishing principal electrical paths from particular first contacts to particular second contacts and to the respective devices connected thereto, portions of said principal paths being in common thereby establishing secondary paths between various pairs of said first contacts; glow discharge tubes placed in each of said paths and adapted to establish said principal paths as pulse transmitting paths responsive to said source and said secondary paths as non pulse transmitting thereby enabling said first contacts to be electrically isolated one from the other while connected to a plurality of said principal paths.

8. In an electronic circuit as claimed in claim 7 including an additional voltage source continuously biasing said secondary paths against response to said pulse source.

9. In an electronic circuit as claimed in claim 7 wherein

each of said principal paths includes at least two of said tubes in series.

10. In an electronic circuit as claimed in claim 7 wherein said switching means includes manual control means allowing each of said devices a choice of particular ones of said second contacts to which it is connected thereby enabling said devices to be selectively connected to particular ones of said first contacts.

11. In an electronic circuit as claimed in claim 7 wherein said means for connecting said source to said first contacts comprises a rotating type switch, a synchronous motor drive, a variable frequency drive source and a frequency control for said drive source thereby enabling the speed of said pulse generator to be determined by the setting of said control.
